UNITED STATES PATENT OFFICE.

SEBASTIAN L. CALVERT, OF BARTLESVILLE, OKLAHOMA, ASSIGNOR OF ONE-HALF TO
CHARLES F. LEECH, OF BARTLESVILLE, OKLAHOMA.

PUMP.

1,164,917.

Specification of Letters Patent. Patented Dec. 21, 1915.

Application filed July 1, 1913, Serial No. 776,843. Renewed April 30, 1915. Serial No. 25,075.

To all whom it may concern:

Be it known that I, SEBASTIAN L. CALVERT, a citizen of the United States, residing at Bartlesville, in the county of Washington 5 and State of Oklahoma, have invented new and useful Improvements in Pumps, of which the following is a specification.

This invention is an improved oil pump 10 in the construction, combination and arrangement of devices hereinafter described and claimed, while the piston structure for the pump is described and claimed in a pending application filed July 17, 1914, and 15 bearing Serial Number 861,551.

One object of the invention is to provide an improved pump of this character which includes means for separating the sand and earthy particles from the oil while pumping 20 the oil and causing the sand to be precipitated.

Another object is to effect improvements in the construction of the plunger.

Another object is to effect improvements in 25 the construction of the reducer for connecting the lower end of the sand chamber casing and the working barrel to the upper end of the intake pipe.

In the accompanying drawings: Figure 1 30 is a vertical sectional view of the operating parts of an oil well pump constructed in accordance with my invention. Fig. 2 is a detail elevation, on a larger scale, of the plunger. Fig. 3 is a detail vertical sectional 35 view of the same. Fig. 4 is a detail sectional view of the upper portion of the pump, showing the plunger tube valve and also showing the removable packing head in which the plunger tube operates. Fig. 5 is a 40 similar view of the lower portion of the pump, showing the lower or standing valve and its connections. Fig. 6 is a detail transverse sectional view on the plane indicated by the line α — α of Fig. 1.

45 In accordance with my invention, I provide an outer tubular body 1, which forms a casing for the sand chamber 2, the upper end of the said tubular body being connected by a suitable reducer 3 to the lower end of the 50 pump tube 4 which reaches to the top of the

well and the lower end of the said outer tubular body 1 is screwed to the outer side of the upper portion of a reducer 5, the lower end of the reducer being connected by a sleeve 6 to the upper end of a perforated inlet tube 7, which is arranged in the bottom of the well and in which oil enters by the rock pressure. 55

In the upper portion of the reducer 5 is a threaded opening 8 in which is screwed the lower end of a tubular cage 9, the upper portion of which is closed as at 10 and provided with openings 11 in its wall, the said cage being formed with a valve seat 12 and a ball valve 13 being employed which is arranged 65 in the upper portion of the cage and is adapted to close downwardly on the seat.

In the casing or outer barrel 1 is an inner or working barrel 14 which is of less diameter than the outer barrel, is spaced therefrom and the lower end of which is screwed 70 to the upper end of the reducer as at 15. The upper end of the working barrel is provided with a conical seat 16 having a removable packing head 17 and to the upper end 75 of the working body is screwed the reduced upper end 18 of a tubular or annular shield or apron 19 the diameter of which exceeds that of the working barrel so that the said shield or apron is arranged around and 80 spaced from the upper portion of the working barrel and in and spaced from the outer barrel 1. The lower end of the said shield or apron is open. The working barrel is provided near its upper end, at a point within 85 the shield or apron with openings 20. The plunger 21 which is arranged to operate in the working barrel has a threaded central opening and is screwed to the lower end of a tube 22. Two pairs of split packing rings 90 which are preferably made of brass and are indicated at 23—24 are arranged at some distance apart on the plunger tube, the lower member of the lower packing rings 23 bearing directly on the plunger. A nut 25 is 95 screwed on the plunger tube 22 and bears against the upper side of the upper ring 24 and between the rings 24—25 are a series of valve cups 26 which are made of leather or other suitable material and are separated 100

from each other by washers 27 which are also arranged on the plunger tube 22 and are adapted to fit in the depressed central portions of the valve cups. The length of the 5 plunger tube is such that its upper end extends above the working barrel. The plunger tube is free to move vertically through a central opening in the removable packing head 17 and the upper end of the 10 plunger tube, which is somewhat reduced, is screwed to the lower end of a cage 28 in which is a ball valve 29 which is adapted to close downwardly on the seat 30 with which the cage is provided. The wall of the cage 15 has openings 31 and the cage is closed at its upper end as at 32 and provided with a threaded stem 33 to which is screwed the lower end of a plunger rod 34 which extends to the upper end of the well and is employed 20 to impart vertical reciprocating motion to the plunger and its plunger tube.

The removable packing head 17 is provided on its upper side with rings 35 which fit snugly around the plunger tube and 25 while permitting the plunger tube to reciprocate prevent sand from going through the said removable packing head. The lower end of the removable packing head is tapered to fit snugly in the seat formed at the 30 upper end of the working valve. The removable packing head while forming a packing for the plunger tube at the upper end of the working barrel is readily removable from the working barrel when the 35 plunger top is withdrawn therefrom.

In the operation of my improved oil pump, oil is sucked into the lower portion of the working barrel at each upstroke of the plunger with its tube 22 and valve 29, 40 the valve 13 opening and the valve 29 closing. On each down stroke of the plunger, the valve 29 opens and the valve 13 closes and oil is forced upwardly through the plunger tube 22 and past the valve 29 into 45 and upwardly in the tube 4.

The barrel or outer body 1 fills with oil as the result of the operations of the plunger and is kept full during the operation of the pump and such sand or other like material 50 as is in the oil becomes precipitated and settles in the sand chamber 2 which is formed by the space between the barrel or outer body 1 and the working barrel 14. The openings 20 in the upper portion of the 55 working barrel prevent air from being compressed therein and interfering with the operation of the plunger and the shield or apron 19 which is arranged around the upper end of the working barrel covers the 60 said openings and prevents sand or the like from entering the working barrel, above the plunger through the said opening. The removable packing head 17 forms in effect a stuffing box for the plunger tube and pre-

vents sand from entering the upper portion 65 of the working barrel.

The arrangement and construction of the parts of my improved oil pump are such as to greatly facilitate the assembling and disassembling of the same and, hence, enable all parts of the pump to be readily inspected and repaired, and also enable the sand which accumulates in the sand chamber to be discharged therefrom periodically as needed. 75

While I have herein shown and described a preferred form of my invention, I would have it understood that changes may be made in the form, proportion and construction of the several parts without departing 80 from the spirit of the invention and within the scope of the appended claims.

I claim:

1. In an oil pump, the combination of a working barrel, an outer barrel around and 85 spaced from the working barrel and forming a sand chamber between them, a standing valve at the lower end of the working barrel, a plunger arranged to operate in the working barrel and having a tube extending 90 above the working barrel and being provided with an upwardly opening valve, said plunger comprising a tubular body having a diametrically reduced intermediate portion and a peripheral annular groove, packing 95 rings fitted in the said grooves and cups on the reduced intermediate portions and said end portions, the said packing rings being adapted to fit loosely in the pump barrel and prevent sand or the like from getting to the cups, and a valve at the upper end of the working barrel and through which said tube extends. 100

2. In an oil pump, the combination of a working barrel, an outer barrel around and 105 spaced from the working barrel and forming a sand chamber between them, a standing valve at the lower end of the working barrel, a plunger arranged to operate in the working barrel and having a tube extending 110 above the working barrel and provided with an upwardly opening valve, cups on said plunger, packing rings also on said plunger and arranged above and below the cups, and a packing head at the upper end of the 115 working barrel and through which said plunger tube extends.

3. In an oil pump, the combination of a working barrel, an outer barrel disposed in spaced relation concentrically about said 120 working barrel and defining a sand chamber by the intervening space therebetween, a standing valve at the lower end of said working barrel, a plunger arranged to operate in said working barrel and having a 125 portion extending above said barrel, an upwardly opening valve associated with said extended portion of the plunger, a packing

head surrounding said plunger above the working barrel, a tubular apron disposed concentrically about said working barrel and spaced therefrom and from said outer 5 barrel, said apron having a reduced end portion associated with the upper end of said working barrel, and a packing surrounding said plunger and snugly engag-

ing the walls thereof and said working barrel. 10

In testimony whereof I affix my signature in presence of two witnesses.

SEBASTIAN L. CALVERT.
